UNITED STATES PATENT OFFICE.

CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed September 25, 1924. Serial No. 739,891.

My invention relates to electric switches, and particularly to rotary snap switches. The object of my invention is to provide an improved handle and actuating connection between the handle and the switch spindle.

In the accompanying drawings—

Fig. 1 is a broken side elevation of a rotary snap switch to which my invention is applied in one form;

Fig. 2 is a vertical section through the switch handle detached from the spindle and drawn to a larger scale;

Fig. 3 is a broken inverted plan of the switch handle and the portion of the switch spindle shown in Fig. 2;

Fig. 4 is a partial section on the line 4—4, Fig. 3;

Fig. 5 is a partial section on the line 5—5, Fig. 2, showing the handle in position on the spindle; and

Fig. 6 is an exploded view of the handle and certain of its associated elements.

The present invention is particularly applicable to a rotary snap switch having a handle of the indicating type which must bear a predetermined angular relationship to the switch spindle and to indicating legends, ordinarily formed on the top of the switch cover. I have employed this type of switch to illustrate the invention, although the latter is not thus limited in its utility.

The switch comprises an insulating base 10 from which rises the rotary switch spindle 11, which actuates the switch blades 12. Co-operating stationary contacts (not shown) are enclosed by the switch cover 13 on the upper surface 14 of which are formed legends with which, in the several positions of the switch, the indicating pointer 15 of the switch handle 16 registers. Rigid with the switch blades 12 is a driving lug 17 embraced by the offset opposite ends of the coil spring 18. Also engaged between the ends of the spring is a lug 19 rigid with the spindle 11 and serving to tension the spring on the rotation of the spindle 11 while the switch blades 12 are temporarily detained by an escapement mechanism (not shown).

The upper end of the switch spindle 11 passes through an aperture 20 in the cover and is threaded at 21 for attachment to the switch handle. The drive connection between the handle and spindle is effected,

however, by a dog 22 offset from the washer 23 and resting against the shoulder 24 on the spindle. The threaded end 21 of the spindle is sheared to form flats 25, to which the aperture in the washer 23 is shaped, and the dog 22 thus held against rotation with respect to the spindle. The washer is clamped against the shoulder 24 by a nut 26, with interposed washer 27 having lugs 28 adapted to be bent up against facets of the nut to lock the latter in clamping position.

The handle 16 is recessed from its lower face to afford a well 29 with a lateral bay 30 and annular channel 31. Arranged within the well 29 is a U-shaped frame 32, the legs of which extend the full depth of the well and are provided, intermediate their ends, with laterally extending lugs 33 which, in the inserted position of the frame, register with the channel 31. Also extending into the well and accommodated within the frame 32 is a ferrule 34 tapped to engage the threaded end 21 of the spindle. Swaged on the head of the ferrule is a washer 35 provided with a finger 36 adapted to enter and play longitudinally in the bay 30 while holding the ferrule against rotation with respect to the body of the handle. Interposed between the frame 32 and the ferrule 34 is a coil spring 37 which abuts at one end against the washer 35 and at its opposite end against a spreader disc 38. The latter engages the free ends of the frame 32 and spreads the latter against the sides of the well to engage the lugs 33 in the channel 31, thus locking the frame to the handle body.

A plate 39 against which the disc 38 is thrust by the spring 37, lies against the inner face of the handle and is provided with lugs 40 and 41 at its opposite margins, the lug 40 taking into the bay 30, and the lug 41 taking into a shallow recess 42 to hold the plate against rotation with respect to the handle. Its central aperture 43 guides the ferrule 34, which is free to slide therethrough, and also accommodates the legs of the frame 32. A bearing washer 44, preferably of paper, is interposed between the plate 39 and the top of the cover upon which it rests. The washer is also pierced at 45 to accommodate the legs of the frame 32 which are offset, as at 46, to hold the washer 44 and plate 39 in position.

The drive connection between the handle and the spindle is effected through the dog 22 fast with the spindle. To receive the dog, the washer 44 and plate 39 are apertured at 47 and 48 in register with a pocket 49 in the handle body. As will be noted in Fig. 2, the free end of the dog 22 lies below the upper end of the spindle 11. It is thus possible to obtain a threaded engagement between the spindle and the ferrule 34 before the end of the dog 22 bears against the lower face of the washer 44. In order to screw the handle down upon the spindle, however, it is necessary to draw the handle outward against the action of the spring 37 to maintain a clearance between the dog 22 and the washer 44 while the handle is rotated to turn the ferrule 34 down upon the spindle. Upon the release of the handle, the spring 37 forces the handle down on the spindle and causes the dog 22 to enter the pocket 49.

The construction not only affords a rugged drive connection between the handle and the spindle, but also permits longitudinal adjustment of the handle on the spindle, since the dog 22 is of sufficient length, and the pocket 49 in the handle body is of sufficient depth to insure a proper drive connection to be established when the ferrule has been screwed down only partially upon the threaded end of the spindle.

The construction is simple to manufacture and assemble and is efficient in operation. Various modifications will readily occur to those dealing with the problem without departing from what I claim as my invention.

I claim—

1. An operating handle for a rotary switch comprising a body recessed to form a well with lateral channel, a U-shaped frame arranged in said well and provided with laterally extending lugs adapted to enter said channel, means at the open end of the frame for spreading the latter to

hold said frame lugs in the channel and thus lock the frame in the well, a screw ferrule floating within the frame but held against rotation with respect to the handle, spring means opposing the floating displacement of the ferrule in the frame, a bearing washer below the handle, the free ends of the frame being offset to engage said washer and to hold the frame spreader in position.

2. A switch handle for use with a spindle having an eccentric driving dog fast therewith, said handle comprising a body recessed to form a well, a floating spring-operated ferrule mounted in said well and adapted for screw connection with the spindle, a metal plate at the mouth of the well, said plate being apertured to permit the spindle and its driving dog to pass freely therethrough, means for holding said plate against rotation with respect to the handle, and means for securing said plate and ferrule to the handle.

3. In an electric switch, an operating handle comprising a body recessed to form a well with longitudinally extending bay and circumferentially extending channel, a U-shaped frame fitting in said well and having lugs adapted to enter said channel to lock the frame against displacement, a tapped ferrule lying within the frame and having a laterally extending lug playing in said bay to hold the ferrule against rotation with respect to said body, a coil spring abutting at one end against the head of the ferrule, an abutment for the opposite end of the spring through which abutment the ferrule freely passes, said abutment also serving to hold the frame in locked engagement with the handle body, and frame means for holding said abutment against displacement.

In testimony whereof I have signed my name to this specification.

CARL ERIC ANDERSON.
